UNITED STATES PATENT OFFICE.

MAXIMILIAN DEUTSCHER, OF HEIDELBERG, GERMANY.

AUTOMATIC LUBRICATOR.

1,077,813.

Specification of Letters Patent.

Patented Nov. 4, 1913.

Application filed July 29, 1912. Serial No. 711,988.

To all whom it may concern:

Be it known that I, MAXIMILIAN DEUTSCHER, a citizen of the German Empire, residing at Heidelberg, in the Grand Duchy 5 of Baden, Germany, have invented certain new and useful Improvements in Automatic Lubricators; and I do hereby declare the following to be a full, clear, and exact description of the invention, such as will 10 enable others skilled in the art to which it appertains to make and use the same.

This invention relates to automatic lubricators for the wearing surfaces of machine parts, and it is principally designed for applying oil to the guide rails of elevators.

It is already well known that the lubricating devices for the guide rails and cables of elevators, conveyers and the like may be automatically operated by means of projections provided alongside of, or in the track of the vehicle with the aid of the motion of the elevator itself.

Among other advantages intended to be attained by the use of such apparatus, is 25 the delivery of the lubricant only at considerable intervals of time. The intermittent operation heretofore effected by the projections referred to is effected in the present invention by actuating the lubricator by 30 means of apparatus which frictionally engages the guide rail of the elevator, and has a limited oscillating motion due to up and down movement of the elevator, the friction device running with it upon the guide rail. 35 Each of the oscillations or two or more consecutive oscillations may be utilized for the production of a single working stroke of an oil pump, a press, or other delivery mechanism. The motion of the elevator is thus 40 utilized for imparting an intermittent action to the lubricator without requiring an excessive number of parts or any complicated apparatus.

An important advantage of the present 45 invention is that it dispenses with the necessity of attaching projections to the guide rail which in consequence of the variation of the profile of the rail used, according to the maker and the kind and shape of the 50 lift space, often caused very considerable difficulties.

In the accompanying drawing which illustrates one form of the invention, Figure 1 is a side elevation of the lubricator and a

section of the guide rail. Fig. 2 is a sectional view of the device shown in Fig. 1.

Referring to the drawing by letters of reference, *a* represents the distributing block for spreading the lubricant from the container *b* which is fastened to said block. 60 *c* indicates a small plunger pump, the piston of which moves in and out under the influence of the oscillating lever *f* which is fast 65 on the shaft *e*. Upon this shaft *e* are screwed fast two lever arms *g* and *h* constituting the frictional actuating device. These levers *g* and *h* are resilient in order to press the friction blocks *i* and *k* on their ends 70 against the guide rail *l* of the lift.

The operation of the device is as follows: 75 As soon as the lubricating apparatus connected with the lift moves for instance in the direction of the arrow *m* on Fig. 1, the levers *g* and *h* revolve about the shaft *e* throwing the free ends of the levers upward until the piston of the plunger pump *c* is moved to the end of its inward stroke. 80 The parts of the lubricating apparatus remain in this position as long as the motion continues in the direction of the arrow *m*. 85 As soon as the elevator commences its journey in the opposite direction, the free ends of the levers *g* and *h*, in consequence of the frictional engagement of the blocks *i* and *k* with the guide rail, are moved down, so that 90 the piston of the pump *c* is moved outward. Two turnings in the direction of the travel will, therefore, cause one stroke of the oil pump. The lubricating mechanism may obviously be so arranged that at each motion, 95 a complete stroke of the piston shall be effected. The use of a friction piece or friction pieces on the side surfaces of the guide rail or of two pieces traveling upon the side surfaces of the guide rail has the advantage that the necessary play requisite for the guidance of the lift in the guiding devices is obtained without influencing the action of the device.

The stroke of the levers *g* and *h* may be 100 limited by any suitable means, for instance, by stops or projections on the piston of the pump *c* for limiting the stroke of the latter. As shown the length of the stroke is determined by the stroke of the piston of the 105 pump *c*, since one end of the oscillating lever *f* is connected to the piston, so that when the piston has reached the end of its inward

stroke the arms *g* and *h* of the oscillatory device will be prevented from further upward movement, and when the piston reaches the end of its outward stroke, said arms will 5 be prevented from further downward movement.

It will be understood of course that various changes may be made in the details and arrangement of parts without departing 10 from the spirit and scope of my invention, and that the invention is not limited in its application to the guide rails of elevators, though the illustrated embodiment is especially designed and adapted for such use; 15 but obviously the invention is applicable to various other uses, and the term "guide rail" as used in the specification and claims may refer to any similar or equivalent structure to which the invention may be applied; 20 hence I do not desire to be limited to the specific form of device shown and described, nor restricted in the application of the invention to the specific use stated.

Having now particularly described and ascertained the nature of my said invention and in what manner the same is to be performed, I declare that what I claim is:—

1. The combination with a guide rail for an elevator, of a lubricant container adapted 30 to be reciprocated along said guide rail, means for discharging the lubricant from the container upon the guide rail, and an oscillatory device frictionally engaging said guide rail for actuating said discharging means.

2. The combination with a guide rail for an elevator, of a lubricant container adapted to be reciprocated along said guide rail, means for discharging the lubricant from 40 the container upon the guide rail, an oscillatory device frictionally engaging said guide rail for actuating said discharging means, and means whereby the movement of said oscillatory device is limited in both directions to prevent the portion thereof which frictionally engages the guide rail from leaving the latter.

3. The combination with a guide rail for an elevator, of a lubricant container adapted 50 to be reciprocated along said guide rail, a pump for discharging the lubricant from the container upon the guide rail, an oscillatory device frictionally engaging said guide rail for actuating said pump, and means whereby the stroke of the latter is limited to pre-

vent the portion of said oscillatory device which frictionally engages the guide rail from leaving the latter.

4. The combination with a guide rail for an elevator, of a lubricant container adapted to be reciprocated along said guide rail, means for discharging the lubricant from the container upon the guide rail, and an oscillatory device having a resilient portion frictionally engaging the guide rail for actuating said discharging means. 60

5. The combination with a guide rail for an elevator, of a lubricant container adapted to be reciprocated along said guide rail, means for discharging the lubricant from 70 the container upon the guide rail, and an oscillatory device having a pair of resilient arms frictionally engaging the opposite sides of the guide rail for actuating said discharging means. 75

6. An automatic guide-rail lubricating device comprising a lubricant container movable along the guide-rail, means carried by said container for discharging the lubricant therefrom, and a rocking lever having one 80 arm arranged to contact with said guide-rail and another arm connected with said discharging means, whereby the lubricant is distributed by frictional engagement of the rocking lever with the guide-rail as the 85 container travels back and forth.

7. An automatic guide rail lubricating device comprising a lubricant container movable along the guide-rail, a pump carried by 90 said container for discharging the lubricant therefrom, and a rocking lever having one arm arranged to contact with said guide-rail and another arm connected to said pump.

8. An automatic guide-rail lubricating device comprising a lubricant container movable along the guide-rail, a pump carried by 95 said container for discharging the lubricant therefrom and a rocking lever having one arm arranged to contact with opposite sides of said guide rail and another arm connected to said pump, whereby the lubricant is distributed by frictional engagement of the rocking lever with the guide rail as the container travels back and forth. 100

In testimony whereof I affix my signature 105 in the presence of two witnesses.

MAXIMILIAN DEUTSCHER.
